UNITED STATES PATENT OFFICE.

JOSEPH HENRY GUNBY, OF CHICO, CALIFORNIA, ASSIGNOR OF ONE-HALF
TO THOMAS HIRAM MORGAN, OF BUTTE COUNTY, CALIFORNIA.

FRUIT-TRAY.

SPECIFICATION forming part of Letters Patent No. 737,607, dated September 1, 1903.

Application filed September 8, 1902. Serial No. 122,624. (No model.)

To all whom it may concern:

Be it known that I, JOSEPH HENRY GUNBY, a citizen of the United States, residing at Chico, in the county of Butte and State of California, 5 have invented a new and useful Fruit-Tray, of which the following is a specification.

This invention relates to trays employed for the purpose of drying fruits, vegetables, and similar products, either in the open air or in 10 drying-kilns; and the object of the invention is to produce a simply-constructed easily-handled tray which will contain the minimum amount of material and possess the maximum strength and durability.

15 Another object of the invention is to produce a tray from which broken parts may be readily detached and a new or duplicate part inserted without destroying any part of the tray.

20 The invention consists in certain novel features of the construction, as hereinafter shown and described, and specified in the claims.

In the drawings illustrative of the invention, Figure 1 is a perspective view of one of 25 the improved trays viewed from above. Fig. 2 is a perspective view viewed from beneath. Fig. 3 is a transverse section of a number of the trays superimposed.

Trays of the class to which this invention 30 relates are usually about eight feet long, three feet wide, and about two inches high, the sides and ends of one-inch material and the bottom of thin strips secured by their ends to the bottoms of the sides and further secured by 35 longitudinal cleats outside of the bottom members and with one or more intermediate longitudinal cleats secured by the ends to the end members of the frame and also to the transverse bottom members.

40 In the above construction of trays the parts are all firmly nailed together, and in case of breakage of any part the broken part can be replaced only by partially destroying the tray and expending a large amount of labor thereon.

45 In the improved tray herewith illustrated provision is made for replacing broken parts without disturbing the other parts or partially destroying them.

The improvements may be applied to any 50 sized tray, and consists in side members 10 11, provided with longitudinal grooves or seats

14 15, opening inward and disposed near the bottom of the side members. The end members 12 13 are formed narrower than the side members, with their lower edges in transverse 55 alinement with the upper sides of the longitudinal grooves, as shown, so that the inlets to the longitudinal grooves are unobstructed. The bottom of the tray consists in a plurality of thin flexible strips removably engaging 60 the grooves or seats 14 15 by their ends, as shown, the open ends of the grooves permitting the sections forming the bottom of the tray to be readily inserted without disturbing other parts. When thus arranged and the 65 plurality of sections 16 forming the bottom placed in position, two small nails in the end sections will firmly secure all of the sections in place, as the intermediate sections are prevented from longitudinal or vertical move- 70 ment by the grooves 14 15, and the stationary end sections will prevent any lateral movement to the sections.

By this construction it will be noted the lower edges of the side members 10 11 project 75 below the lower surfaces of the bottom sections 16, and within this space is arranged a diagonal stay-brace 17, secured by its ends only with nails passing through the stay-brace and the end section 16 into the end members 80 12 13. Secured by their ends to the side members 10 11 are transverse tie-braces 18, spaced apart, as shown. Any number of these tie-braces may be employed, but generally four will be sufficient, as shown. These tie-braces 85 18 perform a threefold function—first, as braces to prevent the side members from spreading; second, as supports to the diagonal brace 17 and bottom sections 16, and, third, as cleats to hold the trays separated when a 90 number of them are superimposed, and thus provide for the circulation of air between the trays.

It will be noted that in case of the breakage of one or more of the stay-braces 18 it 95 can be replaced without disturbing any other portion of the tray, and the same is true of the diagonal brace 17, as in the event of the breakage of that portion of the device it is only necessary to split it loose from the nails 100 by which it is secured, remove the broken portion, draw the nails by which it was secured,

insert a new diagonal brace, and nail it fast, all of which may be done without disturbing the tie-braces or any other part.

In the event of the breakage of any of the 5 sections 16, forming the bottom of the tray, the broken sections may be readily removed and a new section "sprung" into its place by bending the section, as illustrated at 19 in Fig. 3, which action may be accomplished, as 10 will be obvious, without disturbing any other part of the tray.

Another very important advantage in this manner of forming the tray is the comparatively few nails required, as in the full-sized 15 standard tray of this construction less than twenty-five nails are required, whereas in a tray of the same capacity as ordinarily constructed from one hundred to one hundred and thirty nails are required to secure the 20 same results.

It will be noted that the transverse tie-braces 18, adjacent to the ends of the tray, are set some distance back from the ends, so that the nails which secure the diagonal brace- 25 member 17 are exposed, whereby they may be inserted and removed without interfering with the transverse tie-bars. By this means the diagonal tie-bar may be readily removed when broken, as above noted, and the nails 30 drawn without interfering with the transverse tie-bar.

The trays may be constructed in any required proportions and modified in minor par-

ticulars without departing from the principle of the invention or sacrificing any of its advantages. 35

Having thus described the invention, what is claimed is—

A fruit-tray comprising side and end members rigidly associated, the side members extending below the end members and being provided in the extended portions with longitudinal grooves extending throughout their entire length and adapted to form seats for transverse members forming the bottom of the tray, a plurality of braces extending transversely across the bottom of the tray and rigidly secured to the under surface of the side members, a diagonally-disposed stay-brace secured at its extremities to the end 40 members of the tray and supported intermediate of its ends by the cross-braces, and a bottom comprising a plurality of flexible strips of wood disposed transversely of the tray and having their ends seated in the 45 longitudinal grooves formed in the side members, the strips at the ends of the bottom being also secured by nails driven through said strips and into the side members. 50

In testimony that I claim the foregoing as 55 my own I have hereto affixed my signature in the presence of two witnesses.

JOSEPH HENRY GUNBY.
